United States Patent [19]

Sugano et al.

[11] Patent Number: Des. 308,050

[45] Date of Patent: ** May 22, 1990

[54] ELECTRONIC COMPUTER

[75] Inventors: Yoshihiko Sugano, Tokyo; Takaharu Andou, Yokohama, both of Japan

[73] Assignee: Kabushiki Kaisha Toshiba,
Kanagawa, Japan

[**] Term: 14 Years

[21] Appl. No.: 130,157

[22] Filed: Dec. 8, 1987

[30] . Foreign Application Priority Data

Aug. 3, 1987 [JP] Japan 62-31261

[52] U.S. Cl. D14/106

CLAIM

The ornamental design for an electronic computer as shown and described.

DESCRIPTION

FIG. 1 is a front, top and right side perspective view of an electronic computer showing our new design,
FIG. 2 is a top plan view thereof,
FIG. 3 is a left side elevational view thereof,
FIG. 4 is a rear elevational view thereof,
FIG. 5 is a bottom plan view thereof,
FIG. 6 is a top plan view thereof, showing the display panel in closing position and supporting leg in retracting position,
FIG. 7 is a right side elevational view thereof also showing the display panel in closing position and supporting leg in retracting position.

FIG.2

FIG.1

F I G.3

F I G.4

F I G. 5

F I G.6

F I G.7
